UNITED STATES PATENT OFFICE.

JOHN ROSS, OF ST. ALBANS, NEW JERSEY.

REFRACTORY GAS FURNACE.

Application filed July 2, 1927. Serial No. 203,029.

This invention relates to gas furnaces and more particularly to those of a regenerative type in which refractory elements are used to produce a uniform heating effect by building up or reverberatory process.

The object of the invention is to provide a furnace or radiator in which gas is consumed, as a fuel, in a particularly economical manner in attaining required temperatures.

10. Other advantageous objects will appear in the following description, taken in connection with the accompanying drawings forming part hereof, and in which:

Figure 1 is a vertical sectional view of a 15 preferred embodiment of the invention, taken substantially on the center line thereof.

Figure 2 is a transverse sectional view taken on line 2—2 of Figure 1.

Figure 3 is an end view thereof, parts being broken away to disclose the interior construction.

Figure 4 is a plan view of the burner drawn to an enlarged scale, partially in section and having a part of the cover broken away to see the interior elements.

Figure 5 is a transverse sectional view taken on line 5—5 of Figure 4.

Figure 6 is a central vertical sectional view of a modified form of construction 30 without a boiler.

Figure 7 is a transverse sectional view taken on line 7—7 of Figure 6.

Figure 8 is an end elevational view of the same.

35. The heater consists of a plurality of upright hollow elements of rectangular cross section having abutting faces held in tight, rigid relation by any of the means usually employed for such purpose.

40. The end elements 10 are supported preferably on legs 11 and have at their upper ends inreaching ledges 12 to support a boiler shell 13 having a domed top and provided with a safety valve 14 and plug 15.

45. A water inlet pipe 16 enters at one end of the boiler and an outlet pipe 17 is connected for delivering steam as may be desired; the boiler is also provided with a water glass 18 and blown off cocks 19 in the customary manner.

50. Between the end elements 10 are other similar elements 20, 21 and 22 all being arranged in a level plane uniform with the outer elements, both at the top and bottom, 55 and all being open at the top to spacedly receive down-reaching hollow water legs 23

in open communication at their upper ends with the interior of the boiler 13, these legs having separator plates 24 extending nearly to their bottoms.

60. At the center, between the innermost pair of elements, is a rectangular combustion chamber 25 surrounded by a space 26 and blending into an enlarged fire box 27 lined with refractory brick 28 at its sides and having an opening in its bottom through which a burner is entered.

65. The burner is supported on a pair of spaced cross beams 30 removably secured to the bottoms of the elements 22 and consists of a hollow rectangular base 31 having an upper flanged section 32 and containing between them a circuitous mixing chamber 33 provided with an opening in the front wall.

70. Fixed in the opening is a Venturi member 34 containing a contracted opening 35 leading outwardly to an air receiving chamber 36 formed in the conical outer element 37 of the venturi, the same having a flanged connection to the burner base and containing 75 an opening engaging the outer end of the element 34 which is used in preference to a Bunsen type of burner.

75. In the outer wall of the Venturi element 37 are a plurality of orifices 38 for the inlet of air and at the center is a threaded opening to adjustably receive a hollow screw 39 in which is a sleeve 40 carrying at its inner end a gas discharge nozzle 41 in axial register with the opening 35 through the 80 venturi.

85. Carried at the outer end of the sleeve 40 is a right angled connection 42 leading to a valve 43 beyond which is a manually operable valve 44 by which the flow of entering gas 90 is adjusted.

95. Extending from the base element 31 are a plurality of spaced upstanding cylindrical bosses 45 containing bored openings 46 communicating with the chamber 33 and set in 100 their upper ends are sleeves 47 which enter a cover plate 48 common to all.

105. Set in the bottom wall of the base member 31 are tubes 49, extending in concentric spaced relation through the sleeves 47, level with the face of the cover, these tubes constituting, in combination with the sleeves, a form of burner tip, supplied with a suitable gaseous mixture from the chamber 33 and also with atmospheric air through the 110 tubes 49.

As has been noted these burner tips are

arranged in the form of a hollow parallelogram, and arranged over each burner is a hollow rectangular radiant 50 to receive the fuel mixture which is ignited at the several openings 50' therein, the flame being directed upon the bricks 28, these radiants being seated at their lower ends in recesses 51 in the cover 48, directly over the burner tips 49.

Within the central space between the radiants 50 are disposed other refractory bricks 52 forming a center and serving to conserve the heat.

Also reaching upward from the base section 32 are supports 44 on which the cover 15 48 is seated as best seen in Figures 4 and 5.

Disposed over the radiants 50 is a hollow deflector 53, supported by the lower end of a short, central leg 54 in open communication with the boiler 13.

20 Leading oppositely outward from the combustion chamber 25 are outlets 55 communicating through registering openings 56, 57, 58 and 59 near the upper ends of the elements 22, 21, 20 and 10, the spent gases returning through openings 60, 61, 62 and 63 to the space 26 and thence outward through a vent 64 to the place of disposal.

In the modification shown in Figures 6, 7 and 8 the boiler is omitted and the device 30 arranged as a plain radiator for direct heating.

In this type the device is composed of two hollow end members 70 provided with legs 71 and having between them a series of hollow elements 72, 73 and 74 at each side of the structure.

An intermediate member 75 at the center containing a combustion chamber 76 open downwardly into a rectangular fire box 77 40 lined with refractory bricks 78 and centrally in the space therebetween are a row of radiants 79 to which combustible gases are delivered through a venturi generally designated by 80, of the same general type as previously 45 described.

Leading oppositely outward from the combustion chamber 76 are registering openings 81, 82, 83 and 84 the last openings communicating with the chambers in the end elements 50 70, heat passing from them through openings 85, 86, 87 and 88 in the adjacent members 72, 73 and 74 to a passage 89 and thence outward through a vent 90 to the atmosphere.

55 Safety valves 91 are also provided for sudden accessions of internal pressure.

Due to baffles interposed in the several hollow radiator elements it will be seen that

hot gases from the burner are compelled to pass in a tortuous path circuitously through the several elements, the effect being to impart a great proportion of the heat to the thin walls of the radiator whereby the same may be radiated usefully outward.

The substitution of a Venturi device for controlling the entering gas and air as shown best in Figure 4 in place of a common type of Bunsen burner, to heaters of the class described have been found to be an advance in the art of great importance.

70 Although I have described my improvements with considerable detail and with respect to certain particular forms of my invention, I do not desire to be limited to such details since many changes and modifications 75 may well be made without departing from the spirit and scope of my invention in its broadest aspect.

Having thus described by invention, what I claim as new and desire to secure by Letters Patent, is:—

1. A heater having a combustion chamber, a brick lined fire box there-below, a series of radiants spaced inwardly from the lining, an air inlet tube for each radiant, a mixing 85 chamber with which the radiants communicate, a venturi to discharge air and gas into the mixing chamber, means for controlling the air passage in the venturi, and a valve controlling the inlet of fuel to said venturi. 90

2. A heater provided with a combustion chamber having a brick lined fire box, a fuel mixing chamber below said box, a cover place on said chamber, a series of radiants fixed on said plate to extend into said box, 95 said radiants communicating with the mixing chamber, a Venturi tube discharging a mixture of combustible gases into said mixing chamber, a valve controlling the inlet of fuel to the venturi, and a separate air inlet 100 to each radiant.

3. A gaseous fuel heater comprising a rectangular combustion chamber having fire brick walls, a plurality of radiants in said chamber, a hollow circuitous mixing chamber below the radiants and in communication therewith, tubes fixed in said chamber to conduct atmospheric air to said radiants centrally of the mixing chamber passages, and independent separately controllable means 110 to control the entry of air and gas to said mixing chamber.

Signed at New York, in the county of New York, and State of New York, this 5th day of March, 1927.

JOHN ROSS.
